(57) **CLAIM**

I claim the ornamental design for a cup holder and covered storage bin for scooters, as shown and described.

DESCRIPTION

FIG. 1 is a perspective view of a cup holder and covered storage bin for scooters, illustrated as in use, showing my new design;

FIG. 2 is an exploded perspective view thereof, showing my new design;

FIG. 3 is a perspective view thereof, showing my new design;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

The broken lines showing a scooter in FIG. 1 are included for the purpose of illustrating the invention in use, and form no part of the claimed design.
